Harlow M. Davis*

UNITED STATES PATENT OFFICE

PERCY E. STEVENS, OF LYNN, MASSACHUSETTS, ASSIGNOR TO UNITED SHOE MACHINERY CORPORATION, OF PATERSON, NEW JERSEY, A CORPORATION OF NEW JERSEY

BINDING STRIP FOR PARTS OF BOOTS AND SHOES

Application filed July 31, 1930, Serial No. 472,117, and in France September 10, 1929.

This invention relates to the manufacture of boots and shoes, and is herein illustrated as embodied in a binding strip adapted to be used to finish the edges of parts of the uppers of boots and shoes to produce what is known in the trade as French binding.

In the manufacture of boots and shoes it is customary to finish certain edges of parts of the uppers by the use of a binding strip having a coating of adhesive substance on one side thereof over which extends a protective strip of fabric. The band of adhesive substance and the protective strip are somewhat narrower than the binding strip so as to leave exposed a marginal portion of the binding strip. A coil of this composite strip is mounted upon a reel associated with a sewing machine and a proper length is stitched to the display side of a shoe part in such manner that the edge of the binding strip along the uncoated marginal portion thereof and an edge of the shoe part are in register, the row of stitches which attach the strip to the part being located close to said registering edges.

The shoe part, with the composite strip thus attached, then goes to the folding machine operator who tears off the protective strip so as to expose the band of adhesive substance and then folds the free portion of the binding strip about the attached portion and about the edge of the shoe part and presses the coated portion of the strip down upon that side of the shoe part which is hidden in the finished shoe.

In order to permit inspection of the adhesive coating while the protective strip is still in place as well as to ensure that no considerable amount of the adhesive coating shall be removed from the binding strip when the protective strip is torn off, there is provided, according to the present invention, a transparent protective strip having a smooth glassy surface. With such a construction the sewing machine operator may readily detect and discard portions of the binding strip upon which the coating of adhesive substance may be discontinuous or markedly insufficient; and the folding machine operator may tear off the protective strip without danger

of removing with it any considerable amount of the adhesive substance.

Referring now to the accompanying drawing,

The figure is a perspective view of a portion 55 of a composite strip in which the present invention is embodied.

The binding strip, which may be of any suitable flexible material and is commonly of silk, is indicated at 1. The coating of adhesive substance, indicated at 3, is somewhat narrower than the binding strip so as to leave uncoated an extent of the marginal portion of the binding strip. The protective strip 5, herein shown as partly torn off so as to expose a portion of the adhesive coating 3, normally covers the coating completely, and is made of a transparent material having a smooth, glassy surface. As examples of suitable substances I may mention, viscose in the form commonly called cellophane, pyroxylin, cellulose acetate, and other similar smooth, glassy, transparent materials which will readily occur as being more or less their equivalents for the purpose in view. The protective strip is herein illustrated as a film of cellophane.

In use a coil of this composite strip is mounted upon a reel which is associated with a sewing machine. The operator directs the free end of the strip upon the display side of a shoe part with an edge of the shoe part in register with the edge of the binding strip and sews the two articles together by a row of stitches which is located close to the edge 7. With a composite strip made in accordance with the present invention, the sewing machine operator may inspect the adhesive coating through the transparent protective strip and thereby avoid sewing to a shoe part 90 any portions of the binding strip on which the coating may be discontinuous or insufficient.

After the sewing operation has been completed, the piece of work, as has been explained, goes to the folding machine operator who tears off the protective strip and folds the binding strip about the edge of the shoe part. Due to the smooth hard glassy surface of the protective strip, the adhesive

coating parts readily from the protective strip and remains intact upon the binding strip.

Although the invention has been set forth as embodied in a particular composite strip, it should be understood that the invention is not limited in the scope of its application to the particular strip which has been shown and described.

10 Having thus described the invention, what is claimed as new and desired to be secured by Letters Patent of the United States is:

15 A binding strip adapted to be stitched along one edge thereof to a shoe part and to have its unattached portion folded about the edge of the shoe part, a coating of adhesive substance spaced from the edge which is to be stitched to the shoe part, and a transparent protective strip having a glassy surface overlying the coating whereby the adhesive substance may be inspected at any time, and remains on the binding strip when the protective strip is torn off preparatory to the folding operation.

20 25 In testimony whereof I have signed my name to this specification.

PERCY E. STEVENS.
